UNITED STATES PATENT OFFICE

2,351,304

FLUID TRANSFER APPARATUS

Warner T. Tabb, Brooklyn, N. Y., assignor to
Eisemann Corporation, a corporation of Dela-
ware.

Original application October 22, 1940, Serial No.
362,179. Divided and this application March
17, 1942, Serial No. 435,117

8 Claims. (Cl. 103—203)

The present invention relates to fluid transfer apparatus and more particularly to pump apparatus adapted to effect transfer of fluids either liquid or gaseous for a variety of purposes, as disclosed in my parent United States Patent No. 2,237,841, issued June 30, 1942, of which the present application is a division.

General objects of the invention are the provisions of such apparatus which is of simple and economical construction with minimization of leakage tendencies, requires little if any careful and costly machining and treating of cooperating parts frictional engagement between which is relatively minimized thus reducing tendency of wear which might eventually require replacement or repair, can be readily and easily assembled and disassembled, is efficient in operation to transfer fluid effectively at a relatively uniform rate and is capable of efficient high frequency operation; and structural embodiments of such apparatus which can readily and economically be made and assembled in mass production while assuring efficient use and operation thereof.

More specific objects of the invention are the provision of such apparatus characterized by a pump chamber formed by cooperation of a casing and a diaphragm having lateral rigidity and certain spring characteristics with diaphragm biasing leaf-like spring structure having certain spring characteristics mounted in the chamber in a manner to provide certain net spring characteristics for combined diaphragm and spring construction; and to provide such apparatus wherein the mounting and characteristics of said diaphragm structure are such that an outwardly projecting diaphragm operating member mounted on the diaphragm is properly and efficiently guided in its operation without necessitating use therefore of bearing supports or like guiding means which might tend to introduce undesirable problems of construction, manufacture and wear; and which assure efficient operation of said apparatus by mechanical means that may tend in operation to flex said diaphragm only inwardly.

Another object of the invention is the provision in such apparatus of suitable fluid passages past a diaphragm biasing spring disc structure within the pump chamber of such a diaphragm pump, either through the diaphragm or around the periphery thereof, which assures efficient use and operation thereof.

A further object of the invention is to provide such diaphragm pump structure which, though adapted to effect operation when mounted in a position other than with the diaphragm thereof

substantially horizontal and the pump chamber thereabove which may be termed the "vertical pump position," it is particularly effective for continuous efficient operation when mounted in such vertical pump position, the casing structure defining at least a portion of the pump chamber, the inlet and outlet passages communicating therewith and valves structures in the passages being such and cooperating in a manner as to assure effective escape of indrawn relatively light foreign fluid, such as air or gaseous liquid when a liquid, e. g. hydrocarbon fuel, is being transferred by the pump.

Other objects of the invention will in part be obvious and will in part appear hereinafter.

The invention accordingly comprises the features of construction, combination of elements and arrangement of parts, which will be exemplified in the construction hereinafter set forth and the scope of the invention will be indicated in the claims.

For a fuller understanding of the nature and objects of the invention, reference should be had to the following detailed description taken in connection with the accompanying drawing, in which:

Fig. 1 is a top plan view of one embodiment of the apparatus of the present invention; and

Fig. 2 is a sectional view taken on line 2—2 of Fig. 1.

Various diaphragm pump structures have been proposed for use in transferring fluids, both gaseous and liquid. For example, such structures have been proposed for use in both mechanical and electrical gasoline injection systems as well as for use in fuel supply systems of internal combustion engines of the Diesel type, oil burners and the like. Many of such structures, however, have been of such construction as to require extremely careful and costly machining and fitting of parts, treating of material to harden frictionally engaging parts, and costly and frequently inefficient provisions of packing to prevent leakage; and have been complicated making assembly and disassembly difficult, subject to wear of frictionally engaging parts making repair or replacement of parts eventually necessary, and inefficient and non-uniform in operation. Further, such structures have been such as to make their use in systems requiring high speed operation, for example fuel supply systems for internal combustion engines, extremely uncertain and unsuitable.

These and other difficulties are efficiently alleviated by the apparatus of the present invention.

which has been found to be highly satisfactory for use, by way of example, in fuel supply systems for Diesel engines. The diaphragm pump structure of the invention has no working parts characterized by frictional engagement of guiding bearings, other than a roller, if desired, used as a cam follower to impart movement to a diaphragm operating member or rod. The diaphragm operating member is preferably anchored to the diaphragm to project outwardly therefrom free from any bearing support. It is guided in its operation solely by the diaphragm having lateral rigidity mounted with peripheral portions thereof seated on a casing cooperating with the former to form a chamber. A leaf-like spring structure is mounted in the chamber with outer portions thereof rigidly supported by the casing and forms a biasing abutment for the central portion of the diaphragm structure to obtain the desired biasing action. The diaphragm structure has certain spring characteristics as does the spring structure and these are so correlated as to give net spring characteristics for the combined spring and diaphragm structures as to make for desired action.

Inlet and outlet passages having valves therein are provided in the casing to communicate with the pump chamber. The apparatus may be used efficiently in a variety of positions but preferably is mounted vertically with the passages communicating with the chamber through the top of the casing and the valves therein positioned angularly with respect to each other. The portions of the seats of said valves, preferably of the check valve type, nearest each other are at highest elevation with that of the outlet valve above that of the inlet valve. This permits effective escape at each pump cycle of indrawn relatively light foreign fluid, such as air and gaseous fuel when liquid fuel is being transferred, whereby tendency to build up in the pump chamber a body of such foreign fluid or gaseous matter that might eventually prevent efficient operation of the pump is eliminated.

Referring to the drawing like numerals refer to like parts throughout. A base member or plate 10 is provided with an annular seat 11 upon which seats the periphery of a diaphragm 12. The diaphragm 12 may comprise one or more laminae of sheet steel and preferably has a gasket ring 13 located on either side of the periphery thereof. A casing 14 of general cup-shape and preferably domed at the top has an annular seating surface 15 adapted to cooperate with the seat 11 on the base 10 to clamp the diaphragm 12 and gaskets 13, 13 therebetween in a fluid-tight manner, suitable screws 16-16 being used to clamp the parts together.

An operating member or a rod 17 is anchored centrally to the diaphragm 12 to project outwardly therefrom. This member preferably comprises a fork 18 between the legs of which is rotatably mounted a roller 19 constituting a cam follower adapted to ride on the outer surface of a cam 20. A flange 21 at the base of the operating member 17 provides a bearing shoulder for a central portion of the diaphragm 12 and an inner stud end 22 thereof projects through a central aperture in the diaphragm 12 and is externally threaded to receive a nut 23 between which and the flange 21 is clamped the diaphragm structure with an interposed washer 24 and suitable gasket rings 25, 25.

The base member 10 is provided centrally with a hole 26 larger than the operating rod 17 and 75

the roller 19 carried thereby to permit without contact free reciprocation of the latter there-through.

The diaphragm 12 and the casing 14 cooperate 5 to provide a pump chamber 27 on the side walls of which are formed a plurality of circumferentially spaced seats 28-28 providing a plurality of intermediate fluid passages 29-29 past the seats 28-28. A diaphragm biasing leaf-like spring structure 30, preferably formed of one or more laminae of sheet steel of disc configuration is mounted in the chamber 27 with its periphery supported on the seats 28-28 preferably with at least small lateral clearance. This spring structure 10 30 is provided with a central aperture 31 which engages over the inner end 22 of the operating rod and the structure mounted thereon preferably receiving the nut 23 with at least small lateral clearance at points of greatest lateral dimension 15 with the portions adjacent the aperture bearing against the washer 24 to form a biasing abutment for the diaphragm structure.

This spring structure 30 may be cupped and positioned as shown in the drawings. Obviously 25 the position of the spring structure 30 may be reversed provided the seats 28-28 and the diaphragm structure or anchorage structure of the operating rod are suitably altered to accommodate such reversal. The position and shape of the 30 spring structure will be largely dictated by the results desired, the dimensions such as relation of thickness of spring structure to diameter, degree of initial cupping, etc. For some purposes substantially flat disc spring structure may be 35 desirable, such as where the diaphragm is to be flexed in opposite directions from an intermediate neutral position which may be determined by a substantially flat diaphragm in the assembly when not stressed. Equalization of such travel results 40 in the least strain on the diaphragm. The use of a flat spring structure assures compactness of pump construction.

A flat or initially uncupped diaphragm, such as 45 that shown by way of example in the drawing, has certain well defined characteristics as a spring in and of itself. These are such as may tend to result in excessive pressure of the cam follower against the cam in the positions of maximum flexure of the diaphragm, such as the innermost 50 position of the diaphragm and associated parts of the structure shown in the drawing. Further in such a structure those characteristics may tend to prevent the cam follower from effectively following the cam in the outermost position of the diaphragm. The plotted curve of those diaphragm characteristics is found to be of great 55 curvature indicating that the rate of change of positive and negative pressures may be of an objectionable degree under certain conditions making it advisable to use very small diaphragm deflections.

This may be compensated for or effectively corrected by the use of an initially cupped spring 60 which has a reverse spring characteristic curve. Net spring characteristics of the combination of such diaphragm and spring structure can thus be obtained which will assure approximately uniform pressure of the cam follower on the cam. Even a less pressure in the innermost position of the diaphragm than in the neutral or outermost 65 positions thereof, or greater pressure in the latter position than when in the neutral position, may be attained by proper predetermined combinations. Thus the spring rigging of the present 70 pump construction while making for simple and

compact pump construction assures long life for the diaphragm and its operating mechanism and efficient pump performance with the use of diaphragm and biasing spring structure of simple design.

The casing 14 is provided with a pair of opposed bosses 32 and 33 having respectively internally threaded recesses 34 and 35 to receive fluid supply and delivery conduits. The recess 34 communicates through the passage 36 with a fluid passage chamber 37 closed at the top by a removable cap 38 on the inlet side and a similar passage 39 communicates with a similar chamber 40 closed by a similar cap 41 on the outlet side. The chambers 37 and 40 constitute the inner ends of the inlet and outlet fluid passages communicating with the pump chamber 27 through suitable valve structure located therein. These valves preferably are of the check valve type so mounted in their respective chambers as to permit fluid to flow into the pump chamber 27 from the inlet side and fluid to flow out of the pump chamber on the outlet side, as indicated in the drawing.

The check valve 42 in the inlet chamber 37, as is more fully described in my copending application Serial No. 362,180, filed October 22, 1940, comprises a sleeve-like cage 43 having a seat 44 formed thereon against which is biased a valve plate 45 by a leaf-like spring structure 46 centrally apertured to receive a stud structure 47 preferably anchored to the valve plate 45, with spacing means 48 interposed between the valve plate structure 45 and the spring structure 46 to form opposed abutments whereby the valve plate can be biased to its seat and the parts of the valve assembled in the cage 43 by a split-ring 49 seated within a groove in the cage 43 and bearing against peripheral portions of the spring structure 46. The base of the cage 43 is machined out at 50 to form a tapered throat for the valve port.

The check valve in the outlet chamber 40 is similar in construction to the check valve in the inlet chamber 37 except perhaps in one particular. The check valve on the inlet side is preferably provided with a hole 51 through the cage 43 which communicates with the annular recess adjacent to and surrounding the valve seat on the chamber side thereof at substantially its highest point as shown. Such a hole having no purpose in the check valve or the outlet passage may be omitted. In the crown of the domed chamber wall adjacent the tapered throat 50 of the outlet valve cage 43 at its point of highest elevation is machined a way 52 to cooperate with the surface of the throat 50 of the outlet valve, the upwardly inclined inner surface of the pump chamber 27 and the hole 51, to provide an escape way for relatively light foreign fluid that may be drawn into the pump chamber with the fluid being transferred, for example, air and fuel fumes, when hydrocarbon fuel is being transferred. This will prevent undue accumulation of gaseous medium in the transfer pump chamber which might tend to affect efficient operation thereof and possibly prevent in the ultimate any transfer of fluid.

Pulsation eliminators may be provided in the inlet and outlet passages by forming recesses 53, 53 in the caps 38 and 41 and trapping a body of air therein by flexible diaphragms 54, 54 of resilient material, such as neoprene, each held in position on an annular seat 55 by a press-fitted ring 56.

By way of example the transfer pump of the present invention may be mounted by means of mounting ears 68—68 on the base member 10 upon the case of a high pressure injecting apparatus for feeding fuel to a Diesel engine. Such injecting apparatus may comprise a plurality of high pressure injecting pump devices, one for each cylinder of the engine, all operated by a common cam. The circumferential surface of this cam may be provided with lobes equal in number to the number of high pressure injecting devices so that each revolution of the cam, such as 20, will result in a number of complete transfer pump cycles equal to the number of high pressure injecting devices each of which is operated during one cam revolution. Such operation obviously will be of very high frequency and it has been found that the apparatus of the present invention with the provision of diaphragm travel of about .0125" on each side of the neutral position will perform its functions under such conditions in a highly satisfactory manner. It will further be noted that with such a mounting of the device all of the parts thereof can easily and readily be assembled from the top.

In operation when the operating rod is lifted upwardly by a cam the resultant inward flexing of the diaphragm against the biasing action of the spring structure minimizes the space of the pump chamber and when the cam permits the operating rod to be moved outwardly by the biasing spring structure partial vacuum is created in the pump chamber producing a differential in pressure on opposite sides of the inlet valve sufficient to open the same and cause fluid to flow into the pump chamber. When the operating rod is again moved inwardly the inlet valve automatically closes, and pressure built up in the pump chamber by inward flexing of the diaphragm causes the outlet valve to unseat and fluid to be delivered through the outlet passage from the pump chamber. When the biasing spring structure is again permitted to move the diaphragm outwardly the outlet valve automatically closes and the cycle is then repeated.

It will thus be seen that the objects set forth above are efficiently attained by apparatus of the present invention and since certain changes may be made in the above construction and different embodiments or the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention what I claim as new and desire to secure by Letters Patent, is:

1. Fluid transfer apparatus comprising, in combination, a casing, a flexible diaphragm peripherally supported on said casing and cooperating therewith to form a pump chamber above said diaphragm, inlet and outlet passages in the top of said casing, valves located in the passages with the seat of the inlet valve inclined with respect to a horizontal plane, the portion of said inlet valve seat at highest elevation being adjacent said outlet valve with at least a portion of the latter being located above the portion of the inlet

valve which is at highest elevation whereby in-drawn relatively light fluid or gases that would otherwise tend to collect immediately below said inlet valve will pass to said outlet valve and escape therethrough, there being no intervening structure to interfere with such flow.

2. Fluid transfer apparatus comprising, in combination, a domed casing, a flexible diaphragm peripherally mounted on said casing, inlet and outlet passage through the top of said casing, inlet and outlet valves respectively located in said inlet and outlet passages, said diaphragm and said valves cooperating with said casing to define a pump chamber above said diaphragm, the portions of said chamber immediately adjacent said inlet valve having defining surfaces inclined with respect to a horizontal plane upwardly toward said outlet valve, so that relatively light fluid or gases that would tend to collect in said chamber adjacent the inlet valve will pass upwardly therefrom toward said outlet valve and escape therethrough.

3. Fluid transfer apparatus comprising, in combination, a domed casing, a flexible diaphragm peripherally mounted on said casing and cooperating therewith to form a pump chamber above said diaphragm, inlet and outlet passages leading to and from the chamber through the top of said casing and converging inwardly toward each other, valve seats and cooperating valves in said passages disposed substantially transversely thereof with the seat of the inlet valve at a lower relative elevation than that of the outlet valve, the wall of said chamber and valves structures being so shaped and constructed as to provide an upwardly inclined way from that portion of the inlet valve on the chamber side at highest elevation to that portion of the outlet valve at highest elevation.

4. Fluid transfer apparatus comprising, in combination, a domed casing to define the upper portion of a pump chamber, inlet and outlet passages in the top of said casing converging downwardly toward each other, valve cages mounted in said passages substantially transversely thereof with that in the inlet passage having a downwardly facing seat and that in the outlet passage an upwardly facing seat at a relatively higher elevation, and an upwardly inclined fluid escape way extending from the chamber side of that portion of the inlet valve seat at highest elevation to the chamber side of that portion of outlet valve seat at highest elevation.

5. Fluid transfer apparatus comprising, in combination, a domed casing to define the upper portion of a pump chamber, inlet and outlet passages in the top of said casing converging downwardly toward each other, valve cages mounted in said passages substantially transversely thereof with that in the inlet passage having a downwardly facing seat and that in the outlet passage an upwardly facing seat with the inlet valve seat nearer the chamber wall than the outlet valve seat, the cage of the inlet valve having a

hole extending therethrough from the chamber side of the valve substantially at the point of highest elevation, and the chamber side of the cage of the outlet valve and the chamber wall between the inlet and outlet passages being so shaped as to form with the hole an upwardly inclined fluid way terminating substantially at the chamber side of that portion of the outlet valve at highest elevation.

10 6. Fluid transfer apparatus comprising, in combination, a casing structure providing a pump chamber, inlet and outlet passages communicating to the pump chamber at closely adjacent points in the top of said casing structure, a valve located in the inlet passage having a seat, said outlet passage having a throat a portion of the margin of which is located at an elevation higher than the elevation at which the highest portion of said seat is located, said casing structure between the highest portion of said seat and the mentioned portion of the margin of the throat of said outlet passage being so shaped and constructed as to provide for free upward passage of in-drawn relatively light foreign fluid and resultant escape of substantially all thereof.

25 7. Fluid transfer apparatus comprising in combination, a domed casing providing a pump chamber, inlet and outlet passages communicating to the pump chamber through the top of said casing, a valve located in the inlet passage having a seat in the throat thereof, said outlet passage having a throat a portion of the margin of which is located at an elevation higher than the elevation at which the highest portion of said seat is located, said casing structure between the highest portion of said seat and the mentioned portion of the margin of the throat of said outlet passage being so shaped and constructed as to provide an upwardly inclined way from the former to the latter for escape of in-drawn relatively light foreign fluid.

30 8. Fluid transfer apparatus comprising, in combination, a domed casing, a flexible diaphragm peripherally mounted on said casing and cooperating therewith to form a pump chamber above said diaphragm, inlet and outlet passages leading to and from the chamber through the top of said casing and converging inwardly toward each other with the outlet passage having a throat, valve seats and cooperating valves in said passages disposed substantially transversely thereof with the highest portion of the seat of the inlet valve located at a lower relative elevation than a portion of the margin of the outlet passage throat, the wall of said chamber between the passages and associated valve and throat structures being so shaped and constructed as to provide an upwardly inclined way from that portion of the inlet valve on the chamber side located at highest elevation to that portion of the margin of the throat of the outlet passage located at higher elevation.

WARNER T. TABB.
